UNITED STATES PATENT OFFICE.

JAMES G. SMITH, OF LITCHFIELD, ILLINOIS.

RAILWAY-TIE AND BRACE.

1,193,080.

Specification of Letters Patent.

Patented Aug. 1, 1916.

Application filed April 22, 1915. Serial No. 23,166.

To all whom it may concern:

Be it known that I, JAMES G. SMITH, a citizen of the United States, residing at Litchfield, in the county of Montgomery and State of Illinois, have invented certain new and useful Improvements in Railway-Ties and Braces, of which the following is a specification.

This invention relates to combined ties and rail braces for railway rails and has for one of its objects to improve the construction and increase the efficiency and durability of devices of this character.

Another object of the invention is to provide a simply constructed device in which the rails are supported both from lateral and vertical movement, while at the same time, the jars and concussions incident to devices of this character are materially reduced.

With these and other objects in view, the invention consists in certain novel features of construction, as hereinafter shown and described and then specifically pointed out in the claims; and in the drawings illustrative of the preferred embodiment of the invention.

Figure 1 is a side elevation partly in section of one of the improved ties and rail braces. Fig. 2 is a side view of one of the improved rail braces with the rails in section. Fig. 3 is a plan view. Fig. 4 is an enlarged section on the line 4—4 of Fig. 1. Fig. 5 is a perspective view of a portion of one of the improved ties. Fig. 6 is a perspective view from beneath of one of the cushion members. Fig. 7 is a perspective view of the rail brace in modified construction.

Corresponding and like parts are referred to in the following description and indicated in all the views of the accompanying drawings by the same reference characters.

The improved device includes a sleeper or tie formed principally of concrete or like material or compound and comprising a body portion, represented as a whole at 10, with upwardly directed terminal portions 12, the inner ends of the portions 12 forming to the outlines of the outer portions of a railway rail, the latter being represented conventionally at 13. Formed in the upper face of the body portion 10 of the tie, near each of the enlarged portions 12 is a recess 14 to receive a bearing member 15 of relatively hard rubber or like yieldable

material. The recess 14 is located beneath the rails 13 so that the bearing members 15 engage the lower surface of the flanges of the rails, the rails thus being supported 60 their full widths by the bearing members. Formed in the bottom of each recess 14 is a cavity or socket 16 to receive a rib 17 directed downwardly from the bearing member 15. By this means the bearing member 65 is prevented from lateral displacement at the ends of the recess. The whole weight of the rails is thus borne by the member 15, as will be obvious. The upwardly directed portions of the tie thus prevent all outward 70 movement of the rails and firmly brace and support the same.

Embedded within the tie are layers of wire cloth webbing, indicated at 18, to reinforce the material of the tie and correspondingly increase its strength and resisting quality. Any required number of the layers 18 may be employed and will preferably be shorter and of less width than the body of the tie so that portions of the concrete will 80 be disposed externally of the edges of the reinforcing members. Thus the reinforcing members are wholly covered and protected and do not show externally of the material of the tie. The body portion of the tie will 85 be of concrete of suitable proportions and the tie will be molded in the ordinary manner but as the molds form no part of the invention, they are not illustrated. Any suitable form of molds may be employed and 90 constructed of any suitable material. The ties may be of any required size but generally the central body portion will be about twelve inches high and nine inches wide, while the projecting portions 12 will extend 95 to a point about even with the bottom of the ball portions of the rails, but these dimensions may be varied as may be required. The total length will generally be about eight feet, or equal to an ordinary tie. 100

Engaged with the rails 13 at the sides of each tie 10 are rail braces, each constructed of coacting members 19—20, the member 19 being reduced at one end as shown at 21 and projecting by the reduced portion beneath the flange of the rail 13 and with an integral rail brace 22 to engage over the flange and against the web and beneath the ball head of the rail. The member 20 is reduced at 23 to bear beneath the opposite rail and provided with a rail brace 24, corresponding to the rail brace 22, and en-

2
gaging against the opposite rail. The combined length of the members 19—20 is less than the distance between the rails so that the confronting ends will be spaced a considerable distance apart as shown. The member 19 is provided with a threaded socket, indicated at 25, while the member 20 is provided with a similar threaded socket 26. The threads of the sockets are right and left handed to receive a bolt 27 with the threads also right and left handed.

At its center the bolt 27 is provided with a wrench receiving enlargement 28. By this means the members 19—20 may be moved away from each other by actuating the bolt 27 as will be obvious, and thus apply a strong outward pressure against the rails to hold them firmly against the enlargements 12 of the tie. Jam nuts 29—30 will preferably be employed to prevent accidental displacement or backward movement of the tie after the latter has been strained, and thus retain the requisite rigidity between the brace and rails.

25 The braces will preferably be located about midway between each pair of ties, but may be located close to the ties, if preferred.

Having thus described the invention, 30 what is claimed as new is:

1. A railway rail support comprising a tie having rail brace portions adapted to bear against the outer faces of the rails and with recesses for cushion mem-

bers, said recesses each having a depression 35 forming a socket, and a cushion member engaging each of said recesses and adapted to support the rails and each having a lug engaging in one of the sockets.

2. A railway rail support comprising a tie having rail brace portions adapted to bear against the outer faces of the rails and with recesses for cushion members, said recesses each having a depression forming a 40 socket, a cushion member engaging each of 45 said recesses and adapted to support the rails and each having a lug engaging in one of the sockets, and spreader devices adapted to engage the inner faces of the rails at each side of the tie and independent thereof. 50

3. A railway rail support comprising a tie of concrete material having integral rail brace portions adapted to bear against the outer faces of the rails and with recesses for cushion members, said recesses each having a depression forming a socket, a cushion member engaging each of said recesses and adapted to support the rails and each having a lug engaging in one of the sockets, and spreader devices adapted to engage the inner faces of the rails at each side of the tie and independent thereof. 55

In testimony whereof I affix my signature in presence of two witnesses.

JAMES G. SMITH. [L.S.]
